UNITED STATES PATENT OFFICE

WILLIAM E. HOKE, OF BALTIMORE, MARYLAND, ASSIGNOR TO DARDELET THREADLOCK CORPORATION, OF NEW YORK, N. Y., A CORPORATION OF DELAWARE

SCREW THREAD GAUGE

Application filed February 21, 1930. Serial No. 430,280.

This invention relates to improvements in screw thread gauges, and has for its principal objects to provide a simple and efficient gauge for testing screw threads, and particularly internal screw threads, as to accuracy of manufacture with respect to their minor diameter; to provide a simple and efficient gauge for internal screw threads of the well known Dardelet type for quickly and accurately gauging their minor diameter or radial displacement of the conoidal thread rib crest locking surface thereof from the thread axis and determining whether the crest size of such threads falls within a permissible range of plus and minus variation from a standard nominal size.

Other objects and advantages of the invention will appear from the following description of the embodiment of the invention illustrated in the accompanying drawing.

In the drawing:

Fig. 1 is a view of the gauge in side elevation and adjusted for free spinning thereon 25 of a nut to be tested;

Fig. 2 a view showing a Dardelet nut being spun upon the gauge for testing;

Fig. 3 a view showing the gauge and nut in minor diameter measuring or indicating 30 relation;

Fig. 4 a side view of the nut displacing slide bar of the gauge; and

Fig. 5 a sectional view on the line 5—5 of Fig. 1.

The gauge comprises a main cylindrical plug member 10, a relatively slidable bar member 11 guided in a longitudinal slot 12 in member 10, said slot extending along one side of member 10 from end to end of the latter member. Plug 10 has an external screw thread 13 formed thereon, which thread is the master or diameter gauging thread and extends from the nut entering end of the plug to a cylindrical finger grip portion 14 40 of the plug at the opposite end of the plug.

Bar 11 is of substantially greater length than the plug so as to project at one end sufficiently beyond the finger grip end of the plug to afford a convenient finger grip on 50 the bar when the opposite end of the bar is

at or adjacent the opposite end of the plug. The thickness of bar 11 is such that the bar has a close sliding fit in slot 12, and the width of the bar and depth of slot 12 are such that the outer edge of the bar lies within the root 55 circle of thread 13 when the bar is in position in the plug.

The slot 12 lies in a radial plane and the inner edge of the bar is pressed against the bottom of the slot by a bowed spring 15. 60 One face of bar 11 is undercut throughout the length of the bar to form an outwardly facing ledge 16 slidably engaged under the middle portion of spring 15, and the adjacent side wall of slot 12 is formed with a 65 recess affording an inwardly facing ledge 17 under which the free ends of the spring are yieldably engaged, the bar having an inclined face portion 18 and the recess having an opposed similarly inclined wall 19 engaging opposite sides of the spring to hold the spring in contact as described with the ledges 16 and 17. The recess is slightly longer than the distance between the ends of the bowed spring to permit compression 70 of the spring in assembling the gauge elements, and the end walls 20 of the recess serve as abutments to prevent material sliding movement of the spring relatively to the plug. The spring thus serves to frictionally hold the bar in endwise adjusted positions of the bar and also to prevent accidental separation or disconnection of the bar from the plug by either endwise or radial movement.

Bar 11 is provided at its outer edge with 75 an integral upstanding nut-displacing tooth or finger 21, of such height as to extend outward beyond the crest of thread 13, and preferably narrower than the nut thread groove and of such height as not to contact 80 the root of the nut thread. Finger 21 also preferably has its side faces 21^a and 21^b which face toward the ends of the plug inclined both radially and transversely relatively to the plug axis to correspond with the lateral 85 inclination and helix angle of the side faces of the rib of the nut thread the gauge is designed to test, as shown.

Coactive graduations are provided on the plug and bar cooperative to indicate 100

whether or not a measured nut or other internal thread is of nominal minor diameter and/or within a predetermined permissible range of plus and minus deviation from 5 nominal crest size or minor diameter. As shown, these graduations consist of an intermediate nominal size graduation 22 and two end or plus and minus limit graduations 23 on member 10 extending to one edge of the 10 slot 12, and a single coactive transverse graduation 24 extending across the upper edge of bar 11. The series of three graduations on plug 10 may be duplicated at the opposite side of the slot, as shown, if desired, the plug 15 graduations being placed upon a plane chordal surface 27 flush with the top of the bar, which surface is formed by slightly cutting away part of the finger grip portion 14 of the plug in the plane of the outer or top 20 edge of bar 11.

The gauge is preferably calibrated as shown so that, when bar 11 is pulled out until graduation 24 is slightly outward beyond the minus limit graduation, finger face 21^b 25 will register with the steep and narrow side face of the shallow buttress thread 13 in one turn of the thread, so that the nut may be freely spun upon the plug with its thread rib running loosely at the lowest part of the 30 thread groove of the plug, as indicated in Figs. 1 and 2, until finger 21 is engaged in a turn of the groove of the nut thread. The remaining wider face of thread 13 makes a 35 small angle with the axial line of the thread and slopes inwardly as it approaches the finger grip end of the plug, so that upon sliding of bar 11 endwise by thrust upon its projecting end, finger 21 will displace the nut 40 axially toward the opposite end of the plug until the crest surface of the nut thread seats firmly upon the wide conoidal crest diameter 45 gauging side face of thread 13 as shown in Fig. 3. If the nut thread is of proper nominal minor diameter, graduation 24 will register with graduation 22. If the nut thread is of acceptable minor diameter, graduation 24 must lie between the graduations 23.

Thread 13 is of the same pitch as the thread the gauge is designed to test and its minor 50 and major diameters should preferably be outside the tolerance limits for the minor diameter of the thread to be gauged, as shown. In gauging Dardelet locking threads, the wider face of thread 13 should 55 preferably make the same angle with the thread axis as the locking crest surface of the thread to be gauged, as shown, this angle being six degrees. In Figs. 2 and 3 a standard Dardelet locking nut 25 is shown 60 engaged with the gauge, and the inclined locking surface at the crest of the thread rib is designated 26.

It will be observed that slide bar 11 with 65 its finger 21 is operative to measure the extent of displacement from the smaller end of the

helical and low angle gauging face of thread 13 required to effect a close fit on said surface of the crest of the nut thread, and that the bar and finger are manually shiftable to effect the necessary axial displacement of 70 the nut on the plug if desired. The bar need not necessarily be used for the latter purpose, however, as the nut will firmly seat on the plug by gravity if the gauge is up-ended, or may be displaced directly by the hand of 75 the operative, and the bar then shifted to gauge the nut thread. After the testing adjustment of the bar is made and the gauge reading noted, the bar is pulled out to the 80 position shown in Fig. 1 and the nut may then be easily backed off the plug.

What I claim is:

1. A gauge for testing internal screw threads of the Dardelet type as to minor diameter, comprising a plug having an external 85 screw thread of the buttress type of the same pitch as the thread to be tested, and minor diameter variation indicating means engageable with one side face of an internal thread screwed upon the plug and mounted in the 90 plug to move longitudinally of the plug.

2. A minor diameter gauge for internal Dardelet screw threads comprising a plug having a threaded portion provided with a longitudinal channel and with an external 95 master screw thread of the buttress type the least steep side face of which thread is the gauging face and makes an angle of six degrees with the axis of the plug, and a bar 100 slidably held in said channel and provided with an outwardly projecting finger receivable in the groove of an internal Dardelet thread screwed upon the plug thread, and means on said bar and plug for indicating the relation between one edge of said gauging face of the plug thread and the seating position of the crest of the internal thread upon said face.

3. A minor diameter gauge for internal Dardelet screw threads comprising a plug 110 provided with a longitudinal channel and with an external screw thread of the buttress type the least steep side face of which thread makes an angle of six degrees with the axis of the plug, and a bar 115 slidably held in said channel and provided with an outwardly projecting finger receivable in the groove of an internal Dardelet thread screwed upon the plug thread, said thread terminating short of one end of the plug and channel, and 120 said bar and plug having graduations between said end of the plug and the thread coactive to indicate whether or not an internal thread seated on said least steep side face of the plug thread is of acceptable crest size. 125

4. A minor diameter gauge for internal Dardelet nut threads comprising a plug having an external screw thread of the buttress type and a longitudinal channel, means 130 slidably mounted in said channel for axially

shifting a nut screwed upon the plug until the crest of the nut thread seats on the least steep side face of the plug thread, and means coactive with said slidible means for indicating whether the nut thread is of acceptable minor diameter.

5. A minor diameter gauge for internal screw threads comprising an externally threaded plug having a longitudinal channel 10 therein, and a bar slidble endwise in said channel and having a finger projecting outwardly beyond the periphery of the plug between the ends of the plug thread for engaging in the groove of an internal thread 15 screwed upon the plug.

6. A minor diameter gauge for internal screw threads comprising an externally threaded plug having a longitudinal channel 20 therein, and a bar slidble endwise in said channel and having a finger projecting outwardly beyond the periphery of the plug between the ends of the plug thread for engaging in the groove of an internal thread screw upon the plug; and means yieldably 25 holding the bar against the bottom of said channel.

7. A minor diameter gauge for internal screw threads comprising an externally threaded plug having a longitudinal channel 30 therein, and a bar slidble endwise in said channel and having a finger projecting outwardly beyond the periphery of the plug between the ends of the plug thread for engaging in the groove of an internal thread 35 screwed upon the plug; and graduations on the bar and plug for indicating predetermined extents of displacement of an internal thread from one side face of the plug thread when an internal thread is in contact with the 40 other side face of the plug thread.

8. A gauge as claimed in claim 2 wherein the bar is longer than the plug to permit hand shifting of the bar from one end of the bar.

9. A gauge as claimed in claim 7, wherein 45 the bar is longer than the plug to permit grasping of one end of the bar for endwise adjustments of the bar in the plug.

10. A minor diameter gauge for internal screw threads comprising a plug having an 50 external master thread of the buttress type, means mounted on the plug to travel lengthwise of the plug within the root cylinder of the master thread and carrying a projection which is engageable with one side face of an 55 internal thread screwed on the master thread, and means on said plug and said traveling means coactive to indicate whether an internal thread nested on the least steep side face of the master thread is of acceptable minor 60 diameter.

In testimony whereof I hereunto affix my signature.

WILLIAM E. HOKE.
